UNITED STATES PATENT OFFICE.

AUGUSTUS M. HAMER, OF GOOSE CREEK, TEXAS.

TONGS.

Application filed June 20, 1921, Serial No. 478,943. Renewed March 31, 1923.

To all whom it may concern:

Be it known that I, AUGUSTUS M. HAMER, a citizen of the United States, residing at Goose Creek, in the county of Harris and 5 State of Texas, have invented certain new and useful Improvement in Tongs, of which the following is a specification.

This invention relates to new and useful improvements in a tong.

10 One object of the invention is to provide a tong which is specially adapted for use in handling pipe, rods and the like and is particularly useful in screwing together and unscrewing joints of pipe.

15 Another object is to provide a tong which may be readily adjusted to pipes and rods of different sizes. With the above and other objects in view the invention has particular relation to certain novel features of construction, operation and arrangement of parts, an example of which is given in this specification and illustrated in the accompanying drawings, wherein:—

20 Figure 1 shows a plan view of a rotary, showing the tong applied to a drill stem, and working in co-operation with a backup post, for the purpose of screwing together and unscrewing the joints of a drill stem.

25 Fig. 2 shows a side view thereof.

30 Fig. 3 is an edge view of the tong.

Fig. 4 is a side view thereof, partially in section, and

35 Fig. 5 is a cross sectional view taken on the line 5—5 of Fig. 4. In the drawings the numeral 1 designates the rotary table, which is mounted on the base 2. The numeral 3 designates the drill stem which is driven by the rotary. The numeral 4 designates a stationary tong which is held in 40 fixed position by a post 5 which upstands from the base 2. This tong 4 is applied to a joint of the drill stem to hold it against turning. Upstanding from the table 1 is a post 6 which rotates the tong 7. This tong

is secured to the joint of the stem to be 45 turned in screwing together or unscrewing said joints of the stem.

The tong 7 is of special construction which will now be described. This tong includes a handle 8 which has a square bearing in 50 which the shank 9 of the slidable jaw 10 slides. This jaw is arcuate and toothed. The inner end of the shank 9 has a swiveling connection with the actuating rod 11 which is threaded through said handle. The 55 outer end of the rod 11 has an eye 12 provided to receive a handle by means of which the rod may be turned to adjust the jaw 10. Pivoted to the handle 8 there is a hook 13 having the removable, arcuate, toothed jaw 60 14, opposing the slidable jaw 10.

The tong is applied to the pipe as shown in Figures 1 and 2 and the rod turned to clamp the jaws on opposite sides of the pipe and by manipulating the tong the joint of 65 pipe to which it is applied may be turned.

What I claim is:—

A tong including a handle formed with a square socket in one end, a jaw having a square shank which has a sliding bearing 70 in said socket, a rod threaded through the other end of said handle and having a swiveling connection with said shank in said socket to adjust same lengthwise, a hook pivoted to the handle, and adapted to work 75 in opposition to said jaw, and a detachable toothed arcuate jaw attachment carried by said hook and opposing the slidable jaw and means for securing said attachment jaw in position in said hook. 80

In testimony whereof I have signed my name to this specification in the presence of two subscribing witnesses.

AUGUSTUS M. HAMER.
